UNITED STATES PATENT OFFICE.

EDWARD LEE DUNN, OF WORCESTER, MASSACHUSETTS, ASSIGNEE TO STANDARD PLUNGER ELEVATOR COMPANY, OF WORCESTER, MASSACHUSETTS, A CORPORATION OF MASSACHUSETTS.

HYDRAULIC-MOTOR-CONTROLLING MECHANISM.

1,242,928.

Specification of Letters Patent. Patented Oct. 16, 1917.

Application filed October 12, 1915. Serial No. 55,387.

To all whom it may concern:

Be it known that I, EDWARD L. DUNN, a citizen of the United States, residing at Worcester, in the county of Worcester and State of Massachusetts, have invented certain new and useful Improvements in Hydraulic - Motor - Controlling Mechanism, of which the following is a full, clear, and exact specification.

10 This invention relates to hydraulic motors, and has particular reference to a controlling mechanism whereby the speed of a hydraulic motor may be automatically maintained at a predetermined rate irrespective 15 of the load.

The invention is shown herein applied to a hydraulic elevator of the direct plunger type, and adapted for maintaining the speed of either ascent or descent of the elevator 20 constant, whether lightly or heavily loaded.

As shown herein, there is combined with a well known three way valve mechanism, an auxiliary valve mechanism which is so controlled by the flow of the water to or 25 from the main motor as to cause the main controlling valve to assume an open position such as to produce a predetermined speed of the motor at varying loads.

The invention is conveniently applied to 30 power operated hydraulic valves controlled by a pilot valve, and a characteristic feature of the invention is that the automatic devices which control the extent of opening 35 of the main valve operate independently of the pilot valve according to the velocity of the water flowing to or from the motor.

In prior hydraulic valves such as are controlled by a pilot valve, when the motor is running, the opening of the valve is always 40 proportional to the position of the operator's controlling lever. Thus if the operator throws the car lever to extreme position, the main valve opens to extreme position, while if the car lever is partially thrown, the main 45 valve partially opens to a corresponding degree. By this invention, there is interposed between the pilot valve and the main valve motor cylinder, an automatic valve, or valves which are controlled by the flow or velocity of water to or from the main cylinder. These 50 automatic valves really exercise the definitive control of the opening of the main valve, and limit the opening of the main valve so that a predetermined speed cannot

be exceeded, even though the operator on the 55 car may have thrown the car lever to such an extent as to produce an excessive speed in either direction. If the velocity of water to or from the main motor is insufficient to produce the predetermined speed, the automatic devices are ineffective, so that the operator can always obtain the maximum predetermined speed by his car lever, but cannot exceed such speed either with a light ascending load or with a heavy descending 60 load, which are the conditions under which excessive speeds in plunger elevators are produced.

In the specific form of the invention illustrated herein, there is interposed in the to 70 and from pipe, a vane which oscillates a shaft connected to the auxiliary automatic speed controlling valves, there being one valve controlled by oscillation of the vane in one direction, as when the elevator is ascending, and another valve controlled by oscillation of the vane in the opposite direction as when the elevator is descending. These valves are between the pilot valve and the main valve motor cylinder, so that they 75 operate to cut down the amount of water which is applied to move the main valve, and thus stop it when it has opened sufficiently to produce the desired speed. It will thus be seen that the opening of the main 80 valve will vary with the load and speed, but cannot open to such an extent as to produce excess speed. There are numerous advantages for such an arrangement, aside from the assurance of safety against excessive 85 speeds, the principal additional advantage being that there will be a saving in water used to operate the main valve, and also there will not be such excessive fluctuations 90 of pressure in the pressure side of the system, allowing the pumps to operate under a more even load.

In the accompanying drawings, Figure 1 is a view of valve mechanism embodying the 95 invention;

Figs. 2 and 3 are side and end elevations, respectively, and partly in section, showing the vane;

Fig. 4 is a detail on an enlarged scale of the automatic valves, which are controlled 105 by the vane, and

Fig. 5 is an end elevation partly in section of one of the automatic valves.

The main valve, pilot valve, and the automatic valve mechanisms chosen herein to illustrate the application of the invention are substantially the same as similar mechanisms shown in patent to Larsson No. 786,654, dated April 4, 1905, and are shown herein largely in outline for the sake of clearness.

1 represents the main valve cylinder having the supply pipe 2, and the exhaust pipe 3 connected respectively with pipes 4, 5, leading through automatic valves 6, 7, to the to and from pipe 8, the latter pipe being connected to the main cylinder 9, and the 15 cylinder containing the usual plunger 10 and platform 11. 12 represents the pilot valve casing containing the reciprocating pilot valve stem 13, which is controlled by lever 14 and cable 15, the cable being controlled 20 by a hand lever on the car in the usual manner, as shown in the above patent, but not necessary to be illustrated herein.

The pilot valve casing is connected by a pipe 17 to one end of the main valve, so as 25 to apply pressure to the piston 18, or permit water to exhaust from the right side of piston 18. 19 is a coöperating piston on the main valve stem having a packing which slides on the stationary sleeve 20. The 30 motion of the valve stem in one or the other direction is produced by the differential action of this piston 19 and the end piston 18, as is well understood. The main valve also has a rack 22 which engages with a 35 pinion on the pilot valve stem and a worm mechanism so that when the main valve opens the pilot valve is closed in the usual manner. It is by this mechanism that the operator ordinarily determines the extent 40 of opening of the main valve by the position of his car lever. When the piston 19 moves to the left in Fig. 1, it opens the main valve port 23, so that the pressure water can flow from pipe 2 into pipe 4 and thence through 45 automatic valve 6 to pipe 8 and to the motor cylinder 9, to raise the car. When the car is to descend, the main valve moves to the right in Fig. 1 until piston 24 uncovers port 25 so that the water can exhaust from cylinder 9 through pipe 8, down automatic valve 50 7, pipe 5, port 25 and pipe 3. When the main valve is to be moved to the left, the pilot valve is thrown so as to connect the right-hand end of the main valve cylinder 55 1 by pipe 17 to pressure. This is from pipe 17, through pilot valve 12 to pipe 32, through automatic speed valve port 31, to pipe 30 and main pressure supply 2. When the main valve is to be moved to the right 60 60 by pressure on piston 19, the pilot valve will be thrown so as to connect the right side of motor piston 18 to exhaust through pipe 17, pilot valve to pipe 27, through automatic speed valve 28 to pipe 29 and main exhaust 65 3. In each case it will be seen that the auto-

matic speed control valves 28, 31, when closed, will stop the movement of the main valve, even though the pilot valve remains open. 35 represents a vane pivoted on a shaft 36 journaled in pipe 8 and suitably packed. 37, 37 are stops to limit the oscillation of the vane. It will be seen that if the flow is in one direction, the vane will move in that direction, and vice versa, thereby rocking the shaft 36.

In Figs. 4 and 5, the shaft 36 is provided with arms 38, each of which is connected by a link 39 to valve stems 40, 41. These valve stems pass through packings 42, 42 at opposite ends and also through a bushing 43 connecting the pipes 32, 30 and 29, 27. The bushings 43 are provided with graduated holes 44, constituting a graduated port, and these ports are controlled by a piston 45 on the valve stem 41. The valves 45 are unbalanced so that the pressure of the water tends to hold them in open position as shown in Fig. 5, independently of the springs 46. As seen in Fig. 5, the springs 46 are attached at one end to arms 47, carried by the respective valve stems 40, 41, and at the other end pass through lugs 48 carried by the valve casings. The springs are attached to bolts 49 and are adjusted as to tension by nuts 50, so that by adjusting the tension of springs 46, the up and down speeds of the car at which the valves 40 or 41 are actuated, are separately varied. When the car slows up and the valves 28, 31, open, it will be seen that the water pressure will accelerate them, so that interference with the normal pilot valve control will not occur. This is an important feature of this invention, since it is desirable that the speed regulator be inoperative until the predetermined speed is reached, but it must then operate quickly so as to instantly stop further opening of the main valve, and must not prevent speeding up of the main valve when required.

From the foregoing description, it will be seen that this invention automatically governs or limits the stroke of the main valve independently of the operator, the main valve being governed by the speed of the water, independently of the position of the car lever. It is therefore possible with this invention to maintain uniform car speed with variable loads, and with the main valve either wide open or partially so.

While a preferred form of the invention has been illustrated herein, applied to a plunger elevator of well known type, it is to be understood that the invention is not limited to such application, but is applicable to any hydraulic valve mechanism wherein it is desirable to govern the valve opening by the speed of the water passing through the valve. The details of the invention as shown herein can also be modified without

departing from the scope of the invention, which is not to be limited to a single vane for controlling both automatic governing valves, nor to separate governing valves, or a 5 single main valve, nor to the control of both strokes of a hydraulic motor, since various changes in these particulars may be made without departing from the scope of the invention.

10 Having thus described my invention, what I declare as new and desire to secure by Letters Patent of the United States is:—

15 1. The combination with a main valve, of flow controlled means for governing the travel of said valve.

20 2. The combination with a main valve, a pilot valve, and a movable element controlled by the main valve, of means dependent upon the speed of said movable element 20 limiting the movement of the main valve independently of the pilot valve.

25 3. The combination with a main valve controlling a fluid, a movable element controlled thereby, and means affected by said fluid for controlling the movement of said valve.

30 4. The combination with a main valve and a pilot valve connected to be closed by movement of the main valve, of independent means for stopping the main valve at an intermediate point in its stroke.

35 5. The combination with a main valve and a pilot valve connected to be closed by movement of the main valve, of flow controlled means for stopping the main valve at an intermediate point in its stroke.

40 6. The combination with a main valve and a pilot valve connected to be closed by movement of the main valve, of independent valve means for controlling the movement of the main valve.

45 7. The combination with a main valve and a pilot valve connected to be closed by movement of the main valve, of independent automatic valve means for controlling the movement of the main valve.

50 8. The combination with a main valve and a pilot valve connected to be closed by movement of the main valve, of independent flow actuated valve means for controlling the movement of the main valve.

55 9. The combination with a main valve, operating means therefor, and a movable element controlled by said valve of independent means dependent upon the speed of said movable element for limiting the movement of the main valve.

60 10. The combination with a main valve, and operating means therefor, of flow actuated means for limiting the movement of the main valve.

65 11. The combination with a main valve, and operating means therefor, of flow actuated valve means for limiting the movement of the main valve.

12. The combination with a main valve, and operating means therefor, of a pipe connected with said valve, means in said pipe responsive to flow, and means connected thereto for limiting the movement of said main valve. 70

13. The combination with a main valve, and operating means therefor, of a to and from pipe connected with said valve, means in said pipe responsive to flow, and means connected thereto for limiting the opening and closing movements of said main valve. 75

14. The combination with a main valve, and a pilot valve therefor, of a valve between said pilot valve and the main valve 80 for stopping said main valve independently of the pilot valve, and automatic means for actuating said valve.

15. The combination with a main valve, and a pilot valve therefor, of a valve controlling the main valve for stopping said main valve when the pilot valve is open, and means effective when the main valve is open 85 for automatically controlling said valve.

16. The combination with a main valve, and a pilot valve therefor, of an auxiliary normally open valve for controlling the movement of said main valve, and means for closing said auxiliary valve to stop the main valve without closing the pilot valve. 90 95

17. The combination with a main fluid pressure operated valve, and manual controlling means, of pressure and exhaust auxiliary normally open valves for stopping movement of said main valve in opposite directions, and means actuated by flow to or from said main valve for closing one of said auxiliary valves to stop the main valve independently of the manual controlling means. 100 105

18. The combination with a pressure operated, manually controlled main valve, of normally open valves respectively located in the actuated fluid supply and exhaust passages for said main valve, and flow actuated means for closing one or the other of said valves to stop said main valve independently of the manual controlling means. 110

19. The combination with a pressure operated, manually controlled main valve, of normally open valves respectively located in the actuating fluid supply and exhaust passages for said main valve, and a single flow actuated device for closing one or the other of said valves to stop said main valve independently of the manual controlling means. 115 120

20. The combination with a pipe, of a device movable by the flow in said pipe, a main valve, a pilot valve for controlling said main valve, and means controlled by said flow actuated device for limiting, at a predetermined position, opening of said main valve. 125 130

21. The combination with a main valve, of an unbalanced flow controlled valve for governing the travel of said main valve.
22. The combination with a main valve, of an unbalanced, normally open valve, flow controlled means for closing said valve to limit the travel of the main valve, and means for regulating said valve to vary its responsiveness to flow.
10. 23. The combination with an unbalanced valve, of means for holding said valve open, means for adjusting said holding means, flow controlled means for closing said valve against said holding means, and a main valve having its travel limited by the closing of said valve.
24. The combination with a pipe, of a vane movable therein with the flow, a plurality of independently movable valves connected to said vane, means whereby move-

ment of said vane in opposite directions independently actuates one of said valves, and means for restoring said actuated valve to initial position.

25. The combination with a pipe, of a vane movable therein with the flow, a plurality of independently movable valves connected to said vane, means whereby movement of said vane in opposite directions independently actuates one of said valves, means for restoring said actuated valve to initial position, and means for adjusting said restoring means.

In testimony whereof I affix my signature, in presence of two witnesses.

EDWARD LEE DUNN.
